UNITED STATES PATENT OFFICE.

MAURICE J. WOHL, OF BROOKLYN, NEW YORK, ASSIGNOR TO M. J. WOHL AND COMPANY, OF BROOKLYN, NEW YORK, A COPARTNERSHIP COMPOSED OF MAURICE J. WOHL AND MAX MAYER.

ARC-LAMP AND REFLECTOR.

1,235,272.

Specification of Letters Patent. Patented July 31, 1917.

Application filed April 18, 1916. Serial No. 91,868.

To all whom it may concern:

Be it known that MAURICE J. WOHL, a citizen of the United States, and resident of Brooklyn, city of New York, county of 5 Kings, and State of New York, has invented certain new and useful Improvements in Arc-Lamps and Reflectors, of which the following is a specification.

This invention relates to electric arc 10 lamps and reflectors comprising carbons carried within pivoted reflectors and independent of each other and adjusted at a point beyond the reflector regardless of the angle at which the reflector and the carbons 15 are set, the object of the invention being to keep the arc chamber at a distance from the operating mechanism and prevent injury to the latter by the excessive heat from the arc and to be able to throw the light down or 20 upward without moving the whole lamp and its operating mechanism, to trim or insert the carbons in their holders without interfering with the mechanism housing, and the substituting of a dummy instead of the 25 actual carbon for the adjustment of the latter.

These and other objects and details of the invention are more fully described in the following specification, set forth in the 30 claims and illustrated in the accompanying drawings, wherein:

Figure 1 is a vertical sectional view through the mechanism box and one of the reflectors.

Fig. 2 is a horizontal sectional view on the line 2—2 of Fig. 1.

The lamp shown in the drawings may be permanently located at some point or may be portable, and consists of the box 5 for 40 the housing of the carbon adjusters and operating mechanism and which is divided by means of the partition 6 into compartments 7 and 8, the latter containing the solenoids 9 that operate cores 10 having interposed in 45 their length the horizontal springs 11 in which is located the cross bar 12. At each end of this cross bar is secured the rod 13 made up of spring members 14 and extensions 15 whose lower ends are attached to 50 the clutch members 16 of the usual form and supported on the partition 6 to adjust the rods 17 playing through the openings 18 in said partitions and of the same diameter as the carbons.

The rods 17 are substantially dummy carbons and are carried and adjusted in the 55 clutches the same as a carbon pencil. Their upper ends are fitted in a socket 19 having sleeves 20 which slide on guide rods 21 extending from the partition 6 to the top of 60 the box, there being two sets of these rods for each solenoid.

At the front of the box 5 and at each end is the bracket 22 perforated to receive a rod 23 which is the pivot of the reflector 24 and 65 on which it may be turned to the desired angle to project the light of the arc lamp.

The reflector may be of any type with the rear concave surface 25 and flaring front 26, while from top to bottom extend insulated guide rods 28 through which the pivot rod 23 also passes. The rods 28 extend into recesses 27 at the top of the reflectors and the upper carbons 29 and their holders 30 are adapted to move up and down the rod as 70 the carbons are adjusted. The lower or stationary carbons 31 are carried by the holders 32 secured to the lower end of the bars 28 and when originally located is of sufficient length to be about opposite the focal center 80 of the reflector. The carbons and reflector may be said to constitute a light projector which is pivoted on a horizontal axis.

The holders are so perforated as to fit 85 about the rods 28 and be capable of moving along the same, while the outer ends have sockets 33 for the upper carbons 29. The perforated ends of the holders have at one side the eyes 34 in which play the curved rods 35 that are continuations of rods 36 extending from the lower ends of the dummies 17 and moving with the same so as to transmit the adjustment of the rods 17 to the carbons 29 and regulate them according to the requirements of the arcs by means of the 95 electric circuits operating the lamps. The rods 36 play through slots in the lower side of the reflector.

*When the upper or moving carbons are new and before they are worn, the holders 100 30, together with the dummies 17, are elevated to their greatest limit, the former in the recesses 27, and as the carbons shorten, these parts are allowed to drop as shown in Fig. 1.

This view also shows in dotted lines how 105 the entire lamp may be thrown at any desired angle without disturbing the oper-

ating mechanism or interfering with the working of those parts which may be influenced by changing the lines of gravity. The rods 35 being arcs of a circle of which 5 pivot rod 23 is the center, they play through the eyes 34 when the reflector is shifted without interfering with the adjustment of the carbons and always hold the upper ones at the height determined by the clutches 16. 10 It will be observed by referring to Fig. 2 that the lamps are four in number and arranged in pairs, each pair being controlled by a single solenoid. This arrangement insures a constant light in cases where such a 15 light is absolutely needed and secures the separate and independent feed of each upper carbon, also the trimming of the carbons without access to the mechanism box. The substitution of a dummy for the real carbon 20 makes it possible to construct the said dummies of a material easy to feed and adapted to secure a more constant arc.

The whole device may be transported or located in any convenient place for use and 25 its simplicity of construction will preclude any danger of injury or disorder.

It is obvious that the parts may be otherwise arranged or modified without departing from the essential features above described or from the scope of the appended 30 claims.

The circuit for the lamp and its operating mechanism is the usual system employed in electric lamps and the wiring for the same, 35 and the core 10 has at its lower end the plunger 37 to act in the dash pot 38 to prevent the sudden operation of the parts and prevent undue noise.

What I claim as new is:

- 40 1. In an arc lamp, a frame; a light projector comprising a pair of carbons and a reflector, said projector being pivotally mounted on said frame, carbon feed means including a solenoid carried by said frame independently of said projector, and a control connection between the core of said solenoid and one of said carbons adapted to operate in different angular positions of the light projector relatively to the solenoid.
- 45 2. In an arc lamp, a light projector comprising a reflector and a pair of carbons mounted on said reflector, a box containing electrically operated carbon feed mechanism, said projector being pivotally mounted on said box on a horizontal axis, and a control connection between said mechanism and one of said carbons adapted to operate to feed said carbon in different angular positions of the light projector relatively to the said box.
- 50 3. In an arc lamp, a light projector comprising a pair of carbons and a reflector, a box containing electrically operated carbon

feed mechanism, said projector being pivotally mounted on said box on a horizontal axis, and a control connection between said mechanism and one of said carbons adapted to operate in different angular positions of the light projector, said connection including a rod curved concentric to the pivotal axis of the light projector and slidably engaging the carbon holder. 65

4. In an arc lamp, a light projector comprising a pair of carbons and a reflector, a box on which said projector is pivotally mounted on a horizontal axis, an insulated 70 bar carried by and extending vertically in the projector, a carbon holder slidable on said bar, carbon feed mechanism within said box, and a feed control connection between said carbon feed mechanism and said carbon holder. 80

5. In an arc lamp, a light projector comprising a pair of carbons and a reflector, a box on which said projector is pivotally mounted on a horizontal axis, an insulated 85 bar extending vertically in the projector, a carbon holder slidable on said bar, carbon feed mechanism within said box, and a control connection between said carbon feed mechanism and said carbon holder, said connection including a rod curved concentric to the pivotal axis of the projector and slidably 90 engaging the carbon holder.

6. In an arc lamp, a light projector comprising a pair of carbons and a reflector, a 95 box on which said light projector is pivoted on a horizontal axis, a solenoid within the box, a dummy carbon operated by the solenoid, a clutch for adjusting the dummy carbon operated by the core of the solenoid, an 100 insulated bar extending vertically in said projector, a carbon holder slidable on said bar, and a rod secured at one end to the dummy carbon and having its opposite end curved concentric to the pivotal axis of the 105 light projector and in slidable engagement with said carbon holder.

7. In an arc lamp, a light projector comprising a pair of carbons and a reflector, a box behind the said projector and on which 110 the latter is pivoted on a horizontal axis, a solenoid and core, a resilient rod, a clutch, a dummy carbon carried by the said core and adapted to be engaged by the said clutch, a holder for one of said carbons, an insulated 115 bar on which said holder is slidably mounted, an eye on said holder, and a rod secured at one end to the said dummy carbon and having its opposite end curved concentric to the pivotal axis of the light projector and 120 passing freely through the said eye.

Signed at city, county, and State of New York, this 27th day of March, 1916.

MAURICE J. WOHL.
